UNITED STATES PATENT OFFICE.

CHARLES A. MCNEAL, OF NEWARK, OHIO.

ILLUMINATED SIGN.

Application filed November 12, 1923. Serial No. 674,266.

To all whom it may concern:

Be it known that I, CHARLES A. MCNEAL, a citizen of the United States, resident of Newark, in the county of Licking and State of Ohio, have made a certain new and useful Invention in Illuminated Signs; and I declare the following to be a full, clear, and exact description of the same, such as will enable others skilled in the art to which it appertains to make and use the invention, reference being had to the accompanying drawings, and to letters or figures of reference marked thereon, which form a part of this specification.

15 Figure 1 is a face view of the invention. Figure 2 is a section on the line 2—2 of Figure 1.

Figure 3 is a section on the line 3—3 of Figure 1.

20 Figure 4 is a detail perspective view of one of the end sections.

Figure 5 is a detail perspective view of a fragment of one of the interchangeable panels.

25 The invention relates to illuminated signs of sheet metal, having for an object to provide an improved sign of this description which will be light, rigid, and durable, and economical to manufacture.

30 The invention consists in the novel construction and combinations of parts as set forth in the appended claims.

In the accompanying drawings illustrating an embodiment of the invention, the numeral 1 designates the body of the sign composed of two identical interchangeable panels A and B, located edge to edge in the same plane, each composed of a single sheet of metal, the adjacent longitudinal edge portions of which are provided with opposite outwardly bent lapping flanges 2, forming a conduit 3 for the wiring, said conduit bearing a longitudinal row of lamp receptacles 4, wherein are inserted a longitudinal row of lamps 5, the panels being adjacent and parallel and the lamps being common to and illuminating both panels.

35 This being an exterior sign, it is preferable that the conduit be of sufficient size to accommodate two longitudinal rows of opposite lamp receptacles and lamps, the latter projecting oppositely and illuminating the panels upon both sides of the sign.

40 Each of the panels is provided with a longitudinal reversely bent stiffening flange 6, the wiring conduit being preferably of

squared form in cross and the stiffening flange of triangular form in cross section, the lapping flanges 2 being suitably secured together by rivets or the like, and the reversely bent stiffening flanges may have their outer edges lapping the body of the sign and suitably soldered or otherwise secured thereto.

45 The ends of the stiffening flanges are beveled at 7, and an end section 8 is provided for each end of the sign, being of sheet metal of triangular form in cross section preferably and having opposite spaced inner edge portions 9, embracing the transverse margins of said panels, the end sections having beveled ends 10, matching the beveled ends of the stiffening flanges.

50 The resulting sign is designed to save labor and material, and the main body of the sign being composed of two identical interchangeable halves is economical to manufacture.

55 The end sections being slipped over the ends of the panels are suitably fastened to complete the sign.

I claim:

1. In an illuminated sign, two identical interchangeable panels located edge to edge in the same plane and having at their abutting edges a wiring conduit for a single row of lamp receptacles and lamps equidistant from and common to both panels.

65 2. In an illuminated sign, two identical interchangeable panels located edge to edge in the same plane and having at their abutting edges a wiring conduit equidistant from and common to both panels, and a single row of lamp receptacles and lamps carried by said conduit and common to and illuminating both panels.

70 3. In an illuminated sign, two identical interchangeable panels located edge to edge in the same plane and having at their abutting edges a wiring conduit equidistant from and common to both panels, a single row of lamp receptacles and lamps carried by said conduit and common to and illuminating both panels, said panels having each an outer stiffening flange having beveled ends, and an end section having beveled ends and opposite spaced free edge portions fitting over and embracing each end of the sign.

75 4. In an illuminated sign, two identical interchangeable panels located edge to edge in the same plane and having opposite out-

wardly bent lapping flanges forming a conduit equidistant from and common to both panels, a single row of lamp receptacles and lamps carried by said conduit and common to and illuminating one side of both panels, and an oppositely projecting row of lamp receptacles and lamps carried by said conduit and common to and illuminating the other side of both panels.

10 5. In an illuminated sign, two identical interchangeable panels located edge to edge in the same plane and having opposite outwardly bent lapping flanges forming a conduit equidistant from and common to both 15 panels, a single row of lamp receptacles and lamps carried by said conduit and common

to and illuminating one side of both panels, and an oppositely projecting row of lamp receptacles and lamps carried by said conduit and common to and illuminating the other side of both panels, each panel having an outer reversely bent stiffening flange provided with beveled ends, and end sections having beveled ends and embracing the ends of both panels. 25

In testimony whereof I affix my signature.

CHARLES A. McNEAL.
